UNITED STATES PATENT OFFICE.

AUGUST KOTTMANN, OF SOMMERDA, GERMANY, ASSIGNOR TO THE FIRM RHEINISCHE METALLWAAREN- UND MASCHINENFABRIK, OF DUSSELDORF-DERENDFORD, GERMANY.

KEY CANCELING AND LOCKING MECHANISM.

Application filed May 12, 1925, Serial No. 29,672, and in Germany December 24, 1924.

Canceling devices for keyboard mechanisms of calculating and adding machines are known, in which the key-locking bars are canceled or released by a finger, rigidly mounted on the driving shaft, acting in cooperation with a lever locking device. Such devices are suitable for machines in which the driving shaft is only rotated in one direction. In calculating and adding machines, however, in which the driving shaft is rotated in the one or the other direction in accordance with the calculating or mathematical operation to be effected, the cancellation or releasing of the key-locking bars by means of a finger, rigidly mounted on the shaft, is not possible, since the cancellation must always be effected during the last portion of the rotary movement of the shaft in the one or in the other direction. The object of the present invention is to provide canceling means which may be employed for canceling the keys on the rotation of the driving shaft in the one as well as in the other direction, in which case at the same time provision is made for locking the keys, in order to prevent the keys of the key mechanism from being set, when the driving shaft has been moved from its zero position, thus preventing false results from being shown.

According to the invention this is achieved in the following manner. On rotating the driving shaft, the cancellation of the mechanism is effected by an engaging member or the like connected with said shaft engaging a finger, loosely and rotatably mounted on the driving shaft, operating a lever transmission, of the key-locking bars, in dependency on the action of the cancellation device, and the release of the key-locking bar by means of a cam disc mounted on and rotating with the driving shaft.

One form of construction of the device according to the invention is illustrated, by way of example, in the accompanying drawings, in which:—

Fig. 1 shows, partly in section, a side elevation of the device with the driving shaft in its zero position.

Fig. 2 is a similar elevation but showing the driving shaft turned out of its zero position.

A disc 24, having a nose or cam projec-

tion 9, is mounted on the driving shaft 23, which, in order to be rotated, is provided, for example, with a hand crank 7. A finger 15 is loosely and rotatably mounted on the shaft 23, or still better on the hub of the disc 24, the latter carrying pin 25. A double-armed lever 16 is pivotally mounted at 17 on the frame 26 of the calculating machine, and held, under the action of a spring 27, with one of its ends drawn towards the shaft 23. The other end of the double-armed lever 16 acts upon a bell crank lever 20, pivotally mounted on the frame 26; the lever 20 being provided to effect in known manner the moving back of the key-locking bars 2, at the end of the calculating operation, in order to cancel the keys. Pivotally mounted at the rear of the key-locking bars 2 on the frame of the machine is a bell crank lever 11, one arm 28 of which is linked to a rod 29. The rod 29 is slidably arranged in bearings 30 and drawn by a spring 31 against the cam disc 24. Obviously the rod 29 could be provided at its free end with a head or a roller for engaging in a cam groove in the disc 24, in which case the spring 31 could be omitted, and the movement of the bell crank lever 11 would be effected positively.

The operation of the device is as follows:—

On turning the hand crank 7, the disc 24 is likewise rotated. The finger 15 remains in its downwardly directed position until the pin 25 on the disc 24, during the revolution of the latter, engages against the finger 15. From this moment the finger 15 is rotated together with the disc and makes contact with and raises the end of the lever 16, whereupon the other end is moved downward and causes the cancellation in known manner. As soon as the hand crank 7 is moved out of its zero position, the cam 9 of the disc 24 moves out of engagement with the rod 29, which latter, under the action of the spring 31, is moved to the left from the position shown in Fig. 1 into that shown in Fig. 2. The bell crank lever 11 is thereby oscillated so that its free arm is moved upwards into the path of the key-locking bars 2, locking the same against displacement, as shown in Fig. 2. On a further rotation of the hand crank 7 the cam projection 9 en-

gages the rod 29, and returns the latter into the position shown in Fig. 1, so that the free end of the bell crank lever 28 is moved out of the path of the key-locking bars.

5 The same operation of the locking devices is obviously attained, if, as mentioned above, the rod 29 is positively moved to and fro.

Obviously the engaging pin 25 must be mounted on the disc 24, in such relation to 10 the cam projection 9 that the key-locking device may be released before the cancellation of the key mechanism takes place.

I claim:—

1. In a calculating machine including de- 15 pressible operating keys, the combination of spring controlled means for locking said keys in their raised or depressed positions, co-operating means movable to an operative position to fix said locking means against 20 unlocking movements and to a releasing position to permit such unlocking movements, a rotary shaft, controlling means on said shaft controlling the operation of said co-operating means, a finger loosely mounted on said 25 shaft, and means for operatively coupling said finger to said shaft in predetermined relation to said controlling means for moving the key locking means to its inoperative position to release the keys, subsequently to 30 the actuation of said co-operating means to release said key locking means.

2. In a calculating machine including de- 35 pressible operating keys; the combination of spring controlled means for locking said keys in their raised or depressed positions, co-operating means movable to an operative position to fix said locking means against 40 unlocking movements and to a releasing position to permit such unlocking movements, a rotary shaft, a disc fast on said shaft, controlling means combined with said disc controlling the operation of said co-operating means, a finger loosely mounted on said shaft, and a stop on said disc arranged to engage said 45 finger and couple it to said shaft in predetermined relation to said controlling means for moving the key locking means to its inoperative position to release the keys, subsequently to the actuation of said co-operat- 50 ing means to release said key locking means.

3. In a calculating machine including de- 55 pressible operating keys, the combination of spring controlled means for locking said keys in their raised or depressed positions, a ro- 60 tary shaft, a cam disc fast on said shaft, and means operated by said cam disc, on the one hand to permit movement of said locking means to an inoperative position, and on the other hand to adjust the key locking means to an inoperative position to release said keys.

4. In a calculating machine including de- 65 pressible operating keys, the combination of spring controlled means for locking said keys in their raised or depressed positions, 70 co-operating means movable to an operative position to fix said locking means against unlocking movements and to a releasing position to permit such unlocking movements, a rotary shaft, a disc on said shaft, a nose 75 on said disc controlling the operation of said co-operating means, a finger loosely mounted on said shaft, and a pin on said disc arranged to engage said finger and couple it to said shaft in predetermined relation to 80 said nose for moving said key locking means to its inoperative position to release the keys, subsequently to the actuation of said co-operating means to release the key locking mechanism.

5. In a calculating machine including de- 85 pressible operating keys, the combination of a spring controlled bar for locking said keys in the raised or depressed position, means for locking said bar against movement, 90 movable to a position to release the same, means for actuating said bar to release the keys when the bar locking means is moved to release the bar, a rotary shaft, and operating means carried by the rotary shaft for 95 operating the bar locking means and the key locking bar, said operating means being operatively so timed that the bar locking means is actuated to release the bar just before the key locking bar is moved to release the keys.

In testimony whereof I have affixed my signature.

AUGUST KOTTMANN.
